ATTORNEY

UNITED STATES PATENT OFFICE.

HARRIET M. OGAN, OF FORT DODGE, KANSAS.

RAILWAY CONSTRUCTION.

1,278,374.

Specification of Letters Patent. Patented Sept. 10, 1918.

Application filed April 17, 1917. Serial No. 182,681.

To all whom it may concern:

Be it known that I, HARRIET M. OGAN, a citizen of the United States, residing at Fort Dodge, in the county of Ford and State 5 of Kansas, have invented certain new and useful Improvements in Railway Constructions, of which the following is a specification.

This invention relates to railway constructions and has primarily for an object to eliminate the use of wooden ties and to substitute a composition tie therefor to which the rails will be secured without weakening the ties in anyway; to eliminate the use of 10 spikes for securing the rails to the ties; to prevent lateral displacement of the rails even should undue pressure be exerted thereon; and to provide means for positively preventing a partial displacement of any 15 part of the railway.

The above and other objects and advantages of this invention will be in part understood from the following description of the present preferred embodiment, the same being illustrated in the accompanying drawings, in which

Figure 1 is a top plan view of a railway construction made in accordance with my invention.

Fig. 2 is a side elevational view of the same, and

Fig. 3 is a sectional view taken on line 3—3 of Fig. 1 and looking in the direction of the arrows.

In the drawings, a plurality of ties 1 are shown which are preferably made of concrete or some analogous composition and have rails 2 mounted thereon in the usual way. A pair of U-bolts 3 embrace the tie 40 beneath each rail, the U-bolts being provided with reduced screw threaded shanks 4 which project through openings in the base flange of the rails 2 and have nuts 5 threaded thereon.

A trussed bracing structure is arranged 45 between the rails 2 and consists of a bar 6 extending longitudinally of the trackway and transversely of the ties 1 and secured to the upper faces of the latter at points approximately midway between the rails 2. Bars 7 are laid across said bar 6 and are secured thereto by U-bolts 8. It will be noted that the U-bolts 8 embrace the ties 1 intermediate the terminals of the latter, one end of each 55 of said bolts being engaged through the bar

6 and a pair of the bars 7, as shown to advantage in Fig. 3, while the other end merely engages through the bar 6 as shown to advantage in Fig. 1. The opposite ends of the bar 7 are superposed above each other on the 60 base flanges of the rails 2, the bars being held in engagement with said base flanges by the U-bolts 3. It will also be noted that one of the shanks of each pair of U-bolts 3 passes through the ends of the bars 7. 65

In view of the above described construction it will be appreciated that the ties 1 will not in any way be weakened which would be the case if bolts, spikes, etc., were passed through the composition tie, but on 70 the contrary the ties are strengthened by the U-bolts 3 and 8. Moreover the construction between the rails will positively hold the latter from lateral displacement. If undue pressure is brought to bear on said rails, it 75 will be necessary for the entire track construction to move as an entirety which as will be appreciated could not readily occur.

It will be understood that the above description and accompanying drawings comprehend only the general and preferred embodiment of my invention and that various minor changes in details of construction, proportion and arrangement of parts may be made within the scope of the appended 80 85 claims without sacrificing any of the advantages of my invention.

Having thus fully described my invention, what I claim as new and desire to secure by Letters Patent is: 90

1. A railroad construction including U-bolts embracing the tie and engaging the rails, to secure the latter, bracing members extending across the trackway and engaging certain of said bolts to prevent lateral displacement of the rails, and longitudinal 95 brace members between the rails, said longitudinal brace members being bolted to the first mentioned brace members. 100

2. A railroad construction including means for bracing the ties and being engaged with the rails to secure the latter to the ties, intersecting brace bars extending across the trackway and engaged with certain of said tie embracing means to hold said rails from displacement, and longitudinal 105 brace members between the rails, said longitudinal brace members being bolted to the first mentioned brace members at their 110 points of intersection.

3. A railway construction including means for bracing the ties and being engaged with the rails to secure the latter to the ties, bracing bars trussed across the ties and engaged with certain of said embracing means to hold said rails from displacement, a longitudinal brace member between the rails, said longitudinal brace member being

bolted to the first mentioned brace members.

In testimony whereof I affix my signature 10
in presence of two witnesses.

HARRIET M. OGAN.
